(57) **CLAIM**

The ornamental design for a donut mug warmer with mug, as shown and described.

DESCRIPTION

FIG. 1 is a front elevational view of the donut mug warmer with mug.

FIG. 2 is a back elevational view of the donut mug warmer with mug.

FIG. 3 is a perspective view of the donut mug warmer with mug; and,

FIG. 4 is another perspective view of the donut mug warmer with mug.

The broken lines in the drawings are for illustrative purposes only and form no part of the claimed design.
